UNITED STATES PATENT OFFICE

2,680,573

AUTOMATIC TENSION DEVICE

Edward H. Monkley, Worcester, Mass.

Application October 18, 1950, Serial No. 190,699

11 Claims. (Cl. 242—55)

1

This invention relates to new and improved automatic tension devices particularly adapted to the rolling, unwinding, and re-winding of web-like material such as paper, flexible metal, fabrics, cellophane, plastic materials, etc., on cores or mandrels.

In rolling and re-winding there are many problems involved in the tension to be applied to the web being re-wound. For instance, as the roll increases in size as it takes up the web, it is necessary to increase the torque applied to shaft driving the roll as the radius of the roll being wound increases; and at the same time it is necessary to reduce the pull, i. e., tension, on the web as the radius of the roll increases because if the tension is maintained the same throughout the winding of the roll, the outside portion of the wound roll stretches during rolling a great deal more than does the web more nearly toward the center of the roll; since the radius increases, each lap or wind is longer than the one preceding it. Due to this, and to the tendency of the material to return to unstretched condition, the material near the center of the roll will be squeezed as the material returns to normal untensioned condition and pressure is exerted by the outer material upon the inner material causing the latter to expand and slide along the core, thus giving an uneven edge on the roll of wound material.

In the case of plastic or rubber web or in fact any material that can stretch, when wound by means of a slip clutch with manual tension control, it is found that the rolls are irregular at their ends, they have hard and soft spots, and the material at the center or near the core is pushed outwardly axially, due to the irregular application of increased friction in the clutch.

It is the primary object of the present invention to provide an automatic tension device which smoothly, gradually and automatically increases the torque on the driving shaft of the roll while accurately controlling the tension on the web; and another object of the invention resides in the provision of an automatic device for maintaining an even tension on a series of webs all being wound on separate cores but on a single mandrel, particularly in cases where the several webs are of different thicknesses and, therefore, increase in diameter on the cores to varying degrees, thus imparting a varying tension in the absence of the use of the present invention.

Other objects and advantages of the invention will appear hereinafter.

Reference is to be had to the accompanying drawings in which

2

Fig. 1 is a vertical longitudinal section through a device according to the invention;

Fig. 2 is an end view of the clutch and operating means therefor;

Fig. 3 is a section on line 3—3 of Fig. 1;

Fig. 4 is a section on line 4—4 of Fig. 1;

Fig. 5 is an enlarged view of an indicating dial illustrated in Fig. 1;

Fig. 6 is a vertical central section through a modified device;

Fig. 7 is a plan view of a feed screw releasing means looking in the direction of arrow 7 in Fig. 6;

Fig. 8 is a section on line 8—8 of Fig. 6;

Fig. 9 is a section through the roll shaft showing one of the driving disks in elevation;

Fig. 10 is a section through the roll shaft illustrating one of the winding cores; and

Fig. 11 is an enlarged section on line 11—11 of Fig. 1.

As shown in Fig. 1, shaft 10 mounted in bearings 12 on any kind of frame desired as at 14, is used to rotate a core or mandrel 16 to wind up a roll 18 from a web. The material being wound 25 may be of any kind, but one of the main purposes of the present invention is to provide a re-winding device for slitting machines, although the invention is not limited thereto. In any case, it will be appreciated that as roll 18 is wound it increases in radius and this requires greater tension on the clutch or shaft to maintain constant tension on the web.

A sprocket or the like 20 is driven by any suitable power means and is keyed to a pair of clutch members 22, 24. These clutch members are provided with radial slip type teeth as at 26 and they engage with like cooperating teeth 28 on cooperating clutch members 30, 32. The clutch members 22, 24 and the sprocket are mounted on rotary and axially movable bearings 34 and, therefore, rotate freely with respect to the sleeve 36 formed integrally or attached securely to clutch member 30, and fixed to shaft 10 by means 37. The clutch members are provided with legs 35 arranged at an angle forming blades creating a cooling draft, see Fig. 11. The members 22 and 24 are provided with overhanging annular pockets 39 for catching and retaining centrifugally thrown oil or grease, dirt, etc.

The clutch member 32 is non-rotatively but slidably secured to the sleeve 36 as by key 38 working in a complementary keyway. A spring 40 constantly urges clutch member 32 to the left in Fig. 1, disengaging the clutch teeth and releasing members 20, 24.

The clutch member 32 is provided centrally

thereof with a circular bearing 42 providing a rotating mounting for a head 44 having abutting thereon a screw 46, the latter being provided with an adjusting thumb nut 48. The screw 46 is in mesh with a threaded passage in a boss 50 on a lever 52 pivoted at 54 to a part of the framework 14. The other end of lever 52 is secured to a link 56, this link in turn being pivotally secured to a lever 58 pivoted at 60 to a slide 62, the latter being adjustable by means of a bolt 64 in a slot 66 and capable of being tightened up on the slide.

As the lever 58 is pivoted in counterclockwise direction in Fig. 1, it moves link 56 to the left and lever 52 in a counterclockwise direction, to increasingly press clutch member 32 into firmer engagement with clutch part 24, and clutch part 22 therefore into firmer engagement with clutch part 30. There is always slippage between the clutch members but with increasing roll radius, this slippage increases and greater torque is required to maintain constant speed of the web and tension thereon.

Link 56 is preferably divided into two parts 56A and 56B, see Fig. 5, these parts being separated at 68 by a fluid type diaphragm which upon being squeezed between the two parts, increases the pressure in a pipe 70 to register on a dial 72, so that the increase in pressure is measurable thereby.

A gear 74 on shaft 10 is meshed with a gear 76 on a shaft 78 in a box 80, the shaft 78 being provided with a worm 82, in mesh with a worm gear 84, see Fig. 8, so that as shaft 10 rotates, the gear 84 is rotated proportionally thereto. Gear 84 is mounted on an upright sleeve 86 journalled at 88 in the box 80 and this sleeve is provided with a pair of diametrically opposed interior slots 90 into which are received the ends of a pin 92 diametrically disposed in a screw 94. The screw 94 extends upwardly out of the box 80 and terminates in a swivel yoke journalling a roller 96. This roller rides against a fixed plate 98 and as it rises moves lever 58 counterclockwise. Lever 58 and plate 98 are undercut or grooved to accommodate the roller, see 100, Fig. 4.

As shaft 10 rotates, the screw 94 is rotated also and being in mesh with a nut or the like 102, is caused to advance in an upward direction thus clearly moving the lever 58 in a counterclockwise direction as in Fig. 1.

The nut 102 is in two parts 102A and 102B, see Fig. 7, each part being provided with a leg 104, 106 in mesh with a gear 108 turnable by means of a handle 110 to separate the two parts of the nut and release the screw 94. By this means the screw may be quickly and easily returned to its lowermost position, the two halves of the nut acting as a clutch and riding in guideways 112 in the top of the box 80.

It will be seen that by this construction the torque on the shaft 10 is increased proportionally to increase in radius of the roll 18 as it rotates; and furthermore, this relationship is adjustable for materials of different thickness by means of plate 62 which may be shifted to vary the initial angularity of lever 58.

It is, of course, to be understood that the parts are so arranged that when the power is first turned on shaft 10 will rotate but with some slippage as the roll increases in diameter, the slippage increases. Manual adjustment of the torque is necessarily erratic or in steps, and this clearly causes hard and soft spots in the roll and makes the web drift. As increase in torque is required 78

by expanding radius of roll 18, the torque is proportionally increased by the present invention by the gradually greater pressure exerted to the right on clutch part 32 by means of the novel structure described.

Referring now to Fig. 6, there is shown a shaft 120 driven by a sprocket or other driver 122 and mounted in bearings 124 in a frame or other support 126. This shaft drives a mandrel 128 on which is mounted a plurality of individual cores 130. These cores are ordinarily made of paper and they are not secured to the mandrel 128. Each core forms a base for rolling or winding a narrow web thereon as at 132, 134, 136, etc. It is pointed out that even though the individual webs should be slit from a single large roll, nevertheless, the thickness thereof will vary and thus certain of the individual rolls will increase in diameter quicker than others, thereby creating a varied tension on the individual rolls. The modification of the device shown in Fig. 6 automatically renders the tension uniform.

A gear 138 is in mesh with a gear 140, the latter being mounted on a shaft 142 having a worm 25 on it engaged with a worm wheel 144 mounted on a sleeve 146. A screw 148 is slidably but non-rotatably mounted with respect to sleeve 146, and supports a relatively rotatable yoke 150 and roller 152. This mechanism is the same as that shown 30 at Fig. 8, Fig. 7 and Fig. 1. As shaft 120 is rotated, the screw 148 rises with roller 152 riding on fixed plate 154 and moving a lever 156 counterclockwise on a plate 158. This action moves a link 160 to the left and a lever 162 pivoted at 164 35 in a counterclockwise direction. Lever 162 terminates in a roller 166 bearing on a washer 168, the latter being disposed about mandrel 128 and spring pressed toward the lever against roller 166 by a spring 170. The spring 170 finds its 40 other reaction point against a washer 172 which has an inwardly directed lug 174 in groove 176 in the mandrel 128. There is a washer 172 between each core 130 and all of these washers are, therefore, driven by the mandrel. As the shaft rotates, winding the webs on the cores, the pressure on spring 170 is gradually proportionally increased, thus creating a greater and greater driving friction between the various washers 172 and the cores 130 so that the latter are rotated 45 with greater torque applied.

This invention applies also to the unwinding roll as well as the winding roll, as the two rolls both must be controlled to avoid piles, flapping, or sag of the web between the unwinding and the 50 re-winding rolls.

Having thus described my invention and the advantages thereof, I do not wish to be limited to the details herein disclosed otherwise than as set forth in the claims, but what I claim is:

60 1. Device of the class described comprising a roll winding element, means to rotate the same to wind or unwind a web, including a rotary shaft, and means independent of the web and out of contact therewith for automatically controlling the torque applied to the shaft, said means comprising a movable member, means connected to the shaft to move the member constantly as the shaft rotates, a linkage moved by the movable member, a slip clutch having a part thereon on the shaft and another part adapted to be driven, means constantly tending to separate the clutch parts, said linkage bearing on the driven clutch part to force the parts toward each other to an increasingly greater extent as the shaft continues 65

rotation thereof, said linkage including a pivoted lever arranged at an angle to the path of the movable member.

2. Device of the class described comprising a roll winding element, means to rotate the same to wind or unwind a web, including a rotary shaft, and means independent of the web and out of contact therewith for automatically controlling the torque applied to said shaft, said means comprising a movable member, means on the shaft to move the member constantly as the shaft rotates, a linkage moved by the movable member, a slip clutch having a part thereon on the shaft and another part adapted to be driven, means constantly tending to separate the clutch parts, said linkage bearing on the driven clutch part to force the parts toward each other to an increasingly greater extent as the shaft continues rotation thereof, said linkage including a pivoted lever arranged at an angle to the path of the movable member, and means to adjust the angularity of the lever relative to said path.

3. Device of the class described comprising a roll winding element, means to rotate the same to wind or unwind a web, including a rotary shaft, and means independent of the web and out of contact therewith for automatically controlling the torque applied to said shaft, said means comprising a pivoted lever, means to pivot the lever, a movable member operatively connected to the shaft to advance to pivot the lever, a linkage effective to be moved by the lever according to the rotation of the shaft, means to increase torque on the shaft, said last named means comprising a slip clutch, the linkage bearing on the latter to increase the friction thereof as the shaft rotates, said lever pivoting means including an axially movable screw, and a nut for the screw, and means to rotate the screw from the shaft.

4. The device of claim 3 wherein the nut comprises a plurality of parts, and means to separate the nut parts to release the screw.

5. A device of the class described comprising a roll winding element, means to rotate the same to wind or unwind a web, including a shaft, a series of washers axially slideable but non-rotatably mounted on the shaft, cores on the shaft alternating with the washers, means to impart axial pressure on the washers and cores to cause the latter to rotate, and means independent of the web and out of contact therewith designed to constantly increase the pressure as the shaft rotates to increase the driving torque on the cores, said last named means comprising a lever having an end bearing on a washer, means to pivot the lever to increase the bearing pressure, and means actuating the lever pivoting means and driven from the shaft.

6. Roll tension control device comprising a shaft, a roll to be driven on the shaft, a driving element rotatably mounted with respect to the shaft, a pair of oppositely directed outwardly facing slip clutch elements fixed with relation to the driving element, a sleeve on the shaft in fixed relation thereto, a slip clutch element fixed to the sleeve and cooperating with one of the outwardly facing clutch elements, another slip clutch element axially slideable but non-rotatable on the sleeve and cooperating with the other of said outwardly facing clutch elements, said driving element being capable of axial movement relative to the shaft, means resiliently tending to separate the first-named pair of clutch elements

from the second-named sleeve mounted clutch element, means to gradually move the clutch elements into even greater driving contact, said means comprising an element bearing on the axially movable sleeve mounted clutch element and means pressing the same toward the first-named pair of slip clutch elements and in turn pressing the latter toward the fixed-relation sleeve mounted clutch element, said means being actuated by the shaft.

7. Roll tension control device comprising a shaft, a roll to be driven on the shaft, a driving element rotatably mounted with respect to the shaft, a pair of oppositely directed outwardly facing slip clutch elements fixed with relation to the driving element, a sleeve on the shaft in fixed relation thereto, a slip clutch element fixed to the sleeve and cooperating with one of the outwardly facing clutch elements, another slip clutch element axially slideable but non-rotatable on the sleeve and cooperating with the other of said outwardly facing clutch elements, said driving element being capable of axial movement relative to the shaft, means resiliently tending to separate the first-named pair of clutch elements from the second-named sleeve mounted clutch element, means to gradually move the clutch elements into even greater driving contact, said means comprising an element bearing on the axially movable sleeve mounted clutch element and means pressing the same toward the first-named pair of slip clutch elements and in turn pressing the latter toward the fixed-relation sleeve mounted clutch element, said element pressing means including a fixed nut, a threaded member in mesh with the nut, means to rotate the threaded member to advance the same relative to the nut, a connection between the shaft and the threaded member to rotate the latter as the shaft is driven, and means actuated by the threaded member to increase pressure on the element bearing on the axially movable sleeve mounted clutch element.

8. Roll tension control device comprising a roll to be driven, a driven shaft to rotate the roll, a threaded member, a fixed nut for the latter so that the member advances as it is rotated, means on the shaft to rotate the threaded member as the shaft rotates, a lever mounted to be angularly swung by the threaded member as the latter advances, a driving element mounted for relative rotational and axial movement with respect to the shaft, a slip clutch element on the driving element, a slip clutch element fixed to the shaft and cooperating with one of said first-named clutch elements, another slip clutch element axially movable on but non-rotational with respect to the shaft and cooperating with the other of the first-named clutch elements, spring means urging the cooperating clutch elements apart, said lever being effective to gradually force the cooperating clutch elements together as the shaft turns, regardless of the rotation of the driving element.

9. Roll tension control device comprising a roll to be driven, a driven shaft to rotate the roll, a threaded member, a fixed nut for the latter so that the member advances as it is rotated, means on the shaft to rotate the threaded member as the shaft rotates, a lever mounted to be angularly swung by the threaded member as the latter advances, a driving element mounted for relative rotational movement with respect to the shaft, slip clutch elements on the driving element, another slip clutch element axially movable on but

non-rotational with respect to the shaft and cooperating with the first-named clutch element, spring means urging the cooperating clutch elements apart, said lever being effective to gradually force the cooperating clutch elements together as the shaft turns, regardless of the rotation of the driving element.

10. Roll tension control device comprising a roll to be driven, a driven shaft to rotate the roll, a threaded member, a fixed nut for the latter so that the member advances as it is rotated, means on the shaft to rotate the threaded member as the shaft rotates, a lever mounted to be angularly swung by the threaded member as the latter advances, a driving element mounted for relative rotation and axial movement with respect to the shaft, a slip clutch element on the driving element, a slip clutch element fixed to the shaft and cooperating with one of said first-named clutch elements, another slip clutch element axially movable on but non-rotational with respect to the shaft and cooperating with the other of the first-named clutch elements, spring means urging the cooperating clutch elements apart, said lever being effective to gradually force the cooperating clutch elements together as the shaft turns, regardless of the rotation of the driving element, said lever bearing on the axially movable clutch element that is non-rotational on the shaft, and said spring means being arranged against and between the last referred to clutch element and the driving element, and a sleeve mounting for the latter, the shaft-fixed clutch element being on the sleeve and the sleeve being fixed to the shaft, the driving element being journaled on the sleeve and a stop on the sleeve preventing axial movement of the driving element thereon in one direction only.

11. Device of the class described comprising a roll winding element, means to rotate the same to wind or unwind a web, including a rotary shaft, and means independent of the web and out of contact therewith for automatically controlling the torque applied to said shaft, said means comprising a movable member, means on the shaft to advance the member constantly as the shaft rotates, a linkage moved by the movable member, 10 a slip clutch having a part thereof on the shaft and another part adapted to be driven, means constantly tending to separate the clutch parts, said linkage bearing on the center of rotation of the driven clutch part to force the parts toward each other to an increasingly greater extent as the shaft continues rotation thereof, and a pressure indicator in the linkage to measure the degree of thrust on the clutch parts.
